UNITED STATES PATENT OFFICE.

GEORGE S. SKILTON, OF BROOKLYN, NEW YORK.

DESIGN FOR A TRAY.

SPECIFICATION forming part of Design No. 17,032, dated December 21, 1886.

Application filed November 6, 1886. Serial No. 218,221. Term of patent 14 years.

To all whom it may concern:

Be it known that I, GEORGE S. SKILTON, of Brooklyn, county of Kings, and State of New York, have invented and produced a new and original Design for Trays, of which the following is a full, clear, and exact description, reference being had to the accompanying drawings, and to the letters of reference marked thereon.

10 Figure 1 is a plan view showing the form or contour of my newly-designed tray and the principal lines thereof. Fig. 2 is a cross-section through line x x of Fig. 1. Fig. 3 is a plan view showing one manner of decorating or ornamenting the central triangular portion of the bottom, and also the rim or flange, leaving the plain band between these parts in accordance with my design. Fig. 4 is a cross-section through line y y of Fig. 3.

20 In all the figures like letters of reference, wherever they occur, indicate corresponding parts.

The general outline of the tray is triangular in form, and has rounded corners, as plainly shown.

25 A is a gradually-curved rim surrounding the flat or nearly flat bottom and flaring outwardly therefrom. The bottom portion is divided into a triangular figure bounded by the dotted line a a a , Fig. 1, and a band, b b b , which occupies the space between the said triangular figure and the joint between the rim or flange and the bottom. The corners of the triangular figure are rounded slightly, as shown, so that the principal lines of the tray shall be substantially parallel. The interior triangular figure may be ornamented or decorated with any regular, symmetrical, or "all-over" pattern; but the band b is to be left

35 plain, the principal feature of my design be-

ing the plain band surrounding the triangular interior of the bottom and being located within the rim or flange. The rim or flange is shown plain in Fig. 1; but it may be ornamented in any suitable way, as by the patterns d d d . 45 The interior triangular figure of the bottom may be ornamented or decorated with the symmetrical or raised patterns c c c ; but in either case the band b is left plain.

I am aware of the Design patent granted to 50 A. Conradt, April 11, 1876, wherein a tray or salver is shown having an outline of which one side is curved inwardly and located opposite a projecting point, in which the other two sides unite, and I make no claim to such design; but,

Having now fully described my design, what I claim as new herein, and desire to secure by Letters Patent, is—

1. The design for a tray herein described 60 and shown, consisting of the bottom of general triangular form, having each of the corners rounded, a central triangular portion, a plain band surrounding this portion, and an outwardly-curved flange. 65

2. The design for a tray herein described and shown, consisting of the bottom B, of general triangular form, having the rounded corners, the central triangular portion ornamented with symmetrical figures, as c c c , the plain band b , and the rim or flange A, having ornamentations, as d d d . 70

In testimony that I claim the foregoing I have hereunto set my hand in the presence of two witnesses.

GEORGE S. SKILTON.
